CLAIM

The ornamental design of a kiosk, as substantially shown and described.

DESCRIPTION

FIG. 1 illustrates a front perspective view of a kiosk in accordance with the present invention;
 FIG. 2 illustrates a front elevation view thereof;
 FIG. 3 illustrates a rear elevation view thereof;
 FIG. 4 illustrates a right side elevation view thereof;
 FIG. 5 illustrates a left side elevation view thereof;
 FIG. 6 illustrates a top plan view thereof; and,
 FIG. 7 illustrates a bottom plan view thereof.

Broken lines in the drawings are for illustrating environmental structure and form no part of the claimed design.
